DENTAL PROSTHESIS

Jan Zeman, Rue Marterey 50, Lausanne-Suisse,
Brussels, Belgium

Filed Aug. 5, 1957, Ser. No. 676,164

Claims priority, application Belgium Aug. 10, 1956
2 Claims. (Cl. 32—3)

This invention relates to improvements in dental prosthesis, whether partial or complete prosthesis.

The invention relates notably to a valve system for prosthesis, which comprises essentially a cup to be fixed, in the prosthesis at the moment of the molding thereof, to a part of the prosthesis which will be directed towards the dental ridge, and a valve to be arranged and attached in this cup.

According to an embodiment, the cup is of a depth greater than the height of the valve it does receive and is designed to thus leave some free room between its bottom and the valve base, said room being provided with at least one hole which will communicate, through the prosthesis or a tooth, with the inside of the mouth. This cup might be at least slightly in the shape of a truncated cone on the outside and it will advantageously be made of a plastic material, of the synthetic resin type.

According to a particular embodiment, the free room between the cup bottom and the valve base is formed by means of a needle passing diametrically through the cup, near the bottom, said needle thus providing holes through the cup and, on the outside thereof, through the molded prosthesis, so that after removal of said needle, said free room underneath the valve communicates with the mouth inside.

As to the valve itself, it does comprise essentially a cylindrical body having an inside chamber one base of which is provided with an air inlet channel and the other base of which is made up of a separate obturating element having at least one small air passage hole, a valve head, preferably of conical shape being freely arranged in the chamber so as to be able to obturate the air inlet channel and being provided with a shaft which is guided in an opening provided in the separate obturating element.

Other details and features of the invention will stand out from the description given below by way of non-limitative example and with reference to the accompanying drawings, in which:

FIG. 1 is a view in section of the cup and valve arranged in a prosthesis.

FIG. 2 is a view in section of the valve only, the valve head being in another position.

FIG. 3 is a view in section along the line III—III of FIG. 2.

FIGS 4 and 5 show, in plan and side views respectively, a type of core.

FIGS. 6 and 7 show, in plan and side views respectively, a second type of core.

FIG. 8 is a view in section of a part of a prosthesis, obtained when using the core of FIG. 4.

As is known, the shaping of a dental prosthesis is made by means of a counter-mold which itself is made from the mold taken on the gum.

When making the prosthesis on such a counter-mold, several cups will be imbedded in the prosthesis during the molding thereof.

Such a cup 1 is shown imbedded in a prosthesis 2 in FIGURE 1, the face 3 of said prosthesis being the one that will engage the dental ridge. Said cup 1 may be, on the outside, slightly in the shape of a truncated cone and it is made of a suitable material, especially of the synthetic resin type.

2

Said cup 1 is provided in the base thereof with two side openings 4, the purpose of which will be described below and which will be closed during the molding of the prosthesis; there might be provided for this purpose a thin needle 5 passing by the openings 4 through the cup 1. Said openings 4 correspond moreover with channels 6 passing through the prosthesis and thus venting the cup to the mouth inside when the prosthesis is in position.

When the molding of the prosthesis is completed, a valve of the type shown in FIGS. 1 and 2 is placed in the cup. Said valve is arranged over the needle 5 and is attached to the cup 1 by a cement 7, for example of resin type, which is applied in an upper part 8, in the shape of a truncated cone, of the cup 1. So as to improve the attachment, a groove 9 may be provided in the valve body. After setting the valve in position, the needle 5 may thus be removed. It is to be noticed that the cup may, instead of being arranged only in the material and prosthesis is made of, be engaged at least partially in a tooth hollowed out for this purpose; in such a case, the channels 6 mentioned above, which pass through the prosthesis to end in the mouth, are formed in the tooth itself.

The valve shown comprises a cylindrical body 10 having on the inside a chamber 11 with a surface 12 in the shape of a truncated cone which forms a valve seat, on the one end of a channel 13. Said surface 12 in the shape of a truncated cone is not absolutely required and the valve seat might simply be made of the opening marginal edges, which is not in the shape of a truncated cone, of the channel 13. The chamber 11 is closed by a disc 14 which is driven in and is provided with two small peripheral openings 15 and a center guiding hole 16. In this hole may move the stem 17 of a conical valve head 18 which will thus, by moving, rest either by its conical part on the seat 12 or by its base 19 on the disc 14.

The rim-like edge 20 of the cylindrical body 10 is provided so as to prevent the admission of the cement 7 in the channel 13 of the cylindrical body 10 when this latter one is joined to the cup 1 by the cement 7.

As indicated above, the channels 4 of the cup and the channels 6 of the prosthesis vent the chamber 11 to the mouth inside and this through the openings 15; thereby, the suction action happening in the mouth will spread the valve head 18 from its seat 12, so that the air which is between the prosthesis and the dental ridge over which this prosthesis is arranged is sucked towards the mouth inside by passing through the channel 13, the chamber 11, the openings 15, the channels 4 of the cup and the channels 6 of the prosthesis. Due to the vacuum thus created between this prosthesis and the dental ridge, the valve head 18 will again be applied on its seat 12. A very good adhesion of the prosthesis to the jaw is thus secured continuously by the suction action happening at all times in the mouth and which thus insures without a stop a vacuum between the prosthesis and the surface over which it is applied.

So as to improve even more the adhesion of the prosthesis to the jaw, the surface 3 of the prosthesis which engages the dental ridge will be provided with one or several grooves of adequate shape, formed during the molding by suitable cores, for example of the type shown in FIGURES 4 to 7, the core shown in FIGURES 4 and 5 being more specially suitable for upper prosthesis, while the core shown in FIGURES 6 and 7 is better suited for the lower prosthesis.

It is again during the formation of the prosthesis over a counter-mold that a core will be provided thereon so as to form the above grooves. The core shown in FIGURES 4 and 5 is in the shape of a blade 22 with two elongated holes 23, joined together by a narrow part 24. This blade will thus be curved to be applied over the

counter-mold, the narrow part 24 corresponding to the front of the mouth. At the level of the narrow part 24 there will only be a single groove in the prosthesis.

With respect to this core 22 or rather with respect to the grooves formed thereby in the prosthesis, two valves of the above-mentioned type or of some other type, will be arranged substantially at the places indicated in broken lines in 26, that is thus at the ends of the grooves, where both adjacent grooves 25 merge.

For a lower prosthesis use will preferably be made of the core shown in FIGURES 6 and 7. It is again a plate 27 with sidewise projections 28; thereby, the core and the projections thereof form in the prosthesis a continuous groove with varying widths due to the presence of said projections; these projections will enable the formation of a groove insuring a better attachment. The position of the valves with respect to the groove obtained in the prosthesis is shown in broken lines in 29 in FIGURE 6, that is again at both ends of the groove formed.

It is quite clear that the shape of the cores is only given by way of example, as well as the position of the valves in the grooves obtained by means of these cores.

It must moreover be well understood that the invention is in no way limited to the above embodiments, and that many changes may be brought therein without departing from the scope of this patent.

I claim:

1. A dental prosthesis comprising a cup embedded in said prosthesis on the side adjacent to the dental ridge when said prosthesis is considered as positioned in the 30

wearer's mouth, an opening being provided in said prosthesis transversely to the gum, a first opening being provided in said cup towards said dental ridge, a second opening being provided in said cup and communicating with said first opening, said second opening being in aligned relationship with said prosthesis opening, a valve body arranged in the first cup opening, and a valve seat in said valve body, said valve seat being arranged towards said dental ridge and in communicating relationship with said second cup opening so that when said prosthesis is in the wearer's mouth, the dental ridge is in communicating relationship with the inside of the mouth through said valve seat, said second cup opening and said prosthesis opening.

2. A dental prosthesis as claimed in claim 1, in which said second cup opening and said prosthesis opening are arranged so as to determine a straight channel passing through the prosthesis.
